(57) **CLAIM**

The ornamental design for a pair of climbing skin mounting brackets, as shown and described.

DESCRIPTION

FIG. 1 is a front perspective view of the left member of a pair of climbing skin mounting brackets, showing the new design; FIG. 2 is a rear perspective view thereof; FIG. 3 is a top plan view thereof; FIG. 4 is a bottom plan view thereof; FIG. 5 is a first side elevational view thereof; FIG. 6 is a second side elevational view thereof; FIG. 7 is a front side elevational view thereof; FIG. 8 is a rear side elevational view thereof; and, FIG. 9 is a perspective view thereof, shown in a position of use with climbing skin engaged thereto.

The drawings show the design of a left climbing skin mounting bracket suitable for being mounted on a left splitboard half. The ornamental design also includes a right climbing skin mounting bracket for being mounted on a right splitboard half, i.e., the right member being the mirror image of the left member depicted in FIGS. 1 through FIG. 7.

The broken lines showing openings are for the purposes of illustrating environment and form no part of the claimed design.
